UNITED STATES PATENT OFFICE.

JAMES W. HARRINGTON, OF BOSTON, MASSACHUSETTS, ASSIGNOR OF ONE-HALF TO ALBERT H. HARRINGTON, OF BOSTON, MASSACHUSETTS.

PICK.

No. 859,811.

Specification of Letters Patent.

Patented July 9, 1907.

Application filed April 3, 1905. Serial No. 253,481.

To all whom it may concern:

Be it known that I, JAMES W. HARRINGTON, a subject of Great Britain, residing at Boston, in the county of Suffolk and State of Massachusetts, have invented 5 new and useful Improvements in Picks, of which the following is a specification.

The invention relates to an improvement in picks, and particularly to a construction whereby the point or operative end of the pick is removable from the 10 pick body for sharpening or renewal.

The main object of the invention is the production of a pick head having one member arranged for use as a hammer, the other member being suitably formed to receive and removably hold a pick point.

15 The invention will be described in detail in the following specification, reference being had to the accompanying drawing, in which,

Figure 1 is a plan view of a pick head constructed in accordance with my invention. Fig. 2 is a side elevation of the same. Fig. 3 is a perspective view of the pick point removed.

Referring to the drawing, wherein like reference numerals indicate like parts throughout the several views, my improved pick comprises a head 1 having 25 the usual eye 2 for the reception of the handle, and arms or members 3 and 4 projecting from said eye member in about the form of the usual pick head.

The member 3 terminates a short distance from the eye 2 and has a squared end 5 to serve as a hammer, for 30 use in stone breaking or other desired purposes. The member 4 of the pick head is cut-away longitudinally to provide a reduced portion 6 having an end shoulder 7, and a longitudinal projection 8, projecting beyond the shoulder 7. The free end of the projection 8 is 35 formed with a lug 9, coextensive in width with the width of the projection, but of less height than the height of the projection, the lug being preferably arranged about centrally of the end of the projection 8. 40 10 represents the point, having the usual sharpened end 11. The opposite end of the point is reduced at 12 to provide a shoulder 13 and a projection 14, the projection being formed at its free end with a lug 15 similar in size and shape to the lug 9 previously described. In assembling the parts the projection 14 45 of the point rests within the cut-away portion 6 of the head member 4, the lug 15 of the projection 14 seating in a recess 16 formed in the wall of shoulder 7; and the projection 8 of the member 4 seats in the reduced portion 12 of the pick point, with the lug 9 fitting a recess 50 17 formed in the wall of the shoulder 13. A bolt 18 passing transversely through the projections 8 and 14, secure the parts against accidental disconnection.

The pick point may be readily disconnected from the pick head when desired for sharpening, or when the pick is designed for other uses which require a 55 peculiarly shaped point, it being understood that I contemplate the construction of points of various formation and arranged at their rear ends for co-operative engagement with the end of member 4 of the pick head. The lugs 9 and 15 when seated within their 60 respective recesses 17 and 16 operate to prevent any lateral strain on the pick point from breaking the connection between said point and the pick head.

It will be noted that the lugs 9 and 15 are equal in thickness to the respective projections 8 and 14, but of 65 less height than the similar dimension of said projections, whereby the lugs provide squared extensions projecting centrally from the ends of the parts 8 and 14. By this construction the strain incident to the use of the pick is borne by the free ends of the projections, 8 70 and 14, and the locking lugs 9 and 15 are thereby effectively protected against liability of breaking when the pick is in use.

The structure provided is especially adapted for a mining pick, as it provides for the renewal of the pick 75 point, and dispenses with the usual additional pick point of ordinary picks, which extra point has been found very awkward in use in the confined spaces in which miners usually work. Furthermore, another advantage due to my structure is that I am enabled to 80 put practically all of the weight of the pick head in one end, whereby the joint may be made very strong.

Having thus described the invention what is claimed 85 as new, is:

A pick comprising a head with an eye therein, an arm 85 projecting laterally beyond one end of the eye, having a vertical squared faced terminal to provide a hammer head, an extended arm on the other end of the eye having a right angular flat sided cut-away portion to provide a vertical shoulder having a central squared recess therein, 90 a squared lug on the free end of the extension, a pick point having a right angular cut-away portion constructed to conform to the configuration of the cut-away portion of the extension and having a similar shoulder with a squared recess therein to inclose the lug on the free end of the 95 extension, a central squared lug on the inner vertical face of the pick point serving to be inclosed within the squared recess of the extension, openings extending entirely through the cut-away vertical face portions of the extension and the pick point, a bolt for engaging said openings and a nut on said bolt, substantially as specified. 100

In testimony whereof, I affix my signature in presence of two witnesses.

his
JAMES W. X HARRINGTON.
